HOSE STORAGE REEL

Benjamin F. Souther, Seattle, Wash.

Application May 6, 1946, Serial No. 667,628

7 Claims. (Cl. 242—86)

1

This invention relates to a hose storage reel and, more particularly, to a storage and dumping device for fire hoses and the like.

It is an important object of my invention to provide a reel upon which collapsible hose can be rolled and maintained ready for instant use and, when desired, dumped and uncoiled for such use, without the necessity of an unreeling operation.

Another object of my invention is the provision, in a hose reel of the type described, of means whereby the elements forming the reel operate upon the withdrawal of a hose nozzle from a retained position, without requiring other action on the part of the operator to dump and uncoil the stored hose.

A still further and important object of the invention is to provide a separable hose reel having a latching mechanism normally operable to maintain a hose nozzle as the key between the operable elements, and which latching mechanism unlatches upon longitudinal withdrawing movement of the nozzle.

The foregoing objects and others ancillary thereto, I prefer to accomplish as follows:

Upon a wall or bulkhead I mount for hinged movement a reel wall that supports a rotatable hub. Opposite the reel wall is positioned a hinged plate which cooperates with the outer end of the hub to form a reel, being in position, the flanges between which hose may be rolled upon the hub. Means is provided for cranking or turning the hub during a reeling operation. Upwardly directed arms on the wall and the plate elements provide lips positioned closely adjacent to each other and partially aligned with a nozzle-receiving opening in the main wall. A nozzle carried on the hose being stored is inserted through said opening and has on it a cam and a lug. The lug abuts the lips of the wall and plate elements to retain them from swinging to dumping positions. Cam-actuated latching means is mounted to positively retain the reel wall and plate in closed position, and such means is operated by the cam carried by the nozzle.

The novel features that I consider characteristic of my invention are set forth with particularity in the appended claims. The invention itself, however, both as to its organization and its method of operation, together with additional objects and advantages thereof, will best be understood from the following description of an embodiment when read in connection with the accompanying drawings, in which:

Fig. 1 is a face view of a wall portion having mounted thereon my hose reel in storage position;

Fig. 2 is a side view of the storage reel as it appears during dumping of a stored hose;

Fig. 3 is an enlarged vertical sectional view taken on line 3—3 of Figure 1; and

Fig. 4 is a perspective view of a latch member employed in my reel.

2

Upon a wall 10, which may be a portion of a building, a bulkhead in a ship, or the like, and having the opening 12, I mount by means of the hinge pin 14 a reel wall 16 which has an upper lip or edge 18 lying adjacent and partially across the opening 12. Wall 16 has a stop lug 19 which cooperates with shelf 20 to retain the wall in an angular position when it has swung about pin 14.

Shelf 20 stands outward from the upright wall 10 and has on its outer edge hinge 22, which joins shelf 20 and the plate 24. Plate 24 has on its upper portion a lip 26 lying close alongside lip 18 and, also, partially closes the opening 12.

An axle 28 is mounted on the reel wall 16 and supports for rotation the hub 30, which is retained thereon by means of nut 32. The outer end of hub 30 is provided with a square socket opening 34 in line with opening 36 in plate 24. A crank 38 may be inserted through opening 36 into socket opening 34 for manual rotation of hub 30.

A hydrant 40 is positioned adjacent the reel and hose 42 extends between the hydrant and coupling 44 which joins nozzle 46 to the hose.

When the hose is to be reeled upon hub 30, it is laid out as on the deck and folded in the middle, back upon itself. The fold is positioned on the hub and, through the instrumentality of crank 38, is spirally wound about the hub.

Nozzle 46 has on one side a camming element 48 and, oppositely thereto, outstanding lug or shoulder 50. When the nozzle is positioned as in Figure 3, walls 16 and 24 are parallel and lips 18 and 26, respectively, are positioned partially across opening 12 with the lug 50 inboard therefrom. In this arrangement nozzle 46 functions as a latch pin to lips 18 and 26 and wall 10.

Adjacent opening 12 on wall 10 are guideways 40 52, 52 which receive the latch element 54 for slideable movement in a vertical plane. The latch has a handle 55 and arms forming lower fork 56, which straddle the nozzle 46 so that the ends of the fork arms may engage in the lip 26 and hold it close to lip 18 and the two of them against wall 10. Locking pin 58 passes through a suitable opening in one of the guideways 52 and a matching opening 60 in latch member 54. While I have shown this locking pin 58 as a desirable, quickly removed safety element to prevent unauthorized or an accidental dumping from the reel, it will be apparent that such may be omitted if desired.

Assuming that the hose reel is in the position of Figures 1 and 3, and it is wished that the hose be dumped for use, all that an operator need do is withdraw the locking pin 58 and pull upon nozzle 46. First, the cam 48 contacts the closed end of fork 56 and lifts the latch 54 in its guideways so that the lower end of the fork arms no longer retain lips 26 and 28 to wall 10. Normally the weight of the hose and of plate 24 will cause the latter to swing outward and downward free

and away from the hub and hose coil thereabout. Likewise the wall 16 will swing about the pivot pin 14 until stop 19 abuts shelf 20. The hose thereupon is free to fall off the hub 30 as suggested in Figure 2. The operator may then open hydrant 40 and be ready to fight a fire or the like. It will be apparent to those skilled in the art that the hydrant 40 may be alternately operated upon withdrawal of the nozzle in the manner suggested in United States Patent No. 2,320,477.

While I have shown and described particular embodiments of my invention, it will occur to those skilled in the art that various changes and modifications may be made without departing from the invention, and I, therefore, aim in the appended claims to cover all such changes and modifications as fall within the true spirit and scope of my invention.

Having thus described my invention, I claim:

1. A dumpable hose storage reel, comprising: an upright wall hingedly mounted to swing about a lower horizontal axis, a hub rotatably mounted on said wall to turn about a horizontal axis at right angles to said hinged mount of said wall, a plate forming a flange for said hub opposite said wall and having a lower hinge mount, a latch slidably mounted opposite said hinges and adapted to engage said wall and plate upper edges to normally retain them upright, said slidable latch being adapted to receive a hose nozzle, camming means on said hose nozzle operable upon said latch when the nozzle is being removed from association therewith to move said latch to the unlatched position whereupon said hub, wall and plate may move to dump hose therefrom, and a shoulder on said nozzle to engage the latched wall and plate edges and forcibly move them when the nozzle is being removed.

2. A dumpable hose storage reel, comprising: an upright wall hingedly mounted to swing about a lower horizontal axis, a hub rotatably mounted on said wall to turn about a horizontal axis at right angles to said hinged mount of said wall, a plate forming a flange for said hub opposite said wall and having a lower hinge mount, a latch slidably mounted opposite said hinges and adapted to engage said wall and plate upper edges to normally retain them upright, said slidable latch being adapted to receive a hose nozzle, camming means on said hose nozzle operable upon said latch when the nozzle is being removed from association therewith to move said latch to the unlatched position whereupon said hub, wall and plate may move to dump hose therefrom, and a stop on said wall to limit swinging movement.

3. A dumpable hose storage reel, comprising: an upright wall hingedly mounted to swing about a lower horizontal axis, a hub rotatably mounted on said wall to turn about a horizontal axis at right angles to said hinged mount of said wall, a plate forming a flange for said hub opposite said wall and having a lower hinge mount, a latch slidably mounted opposite said hinges and adapted to engage said wall and plate upper edges to normally retain them upright, said slidable latch being adapted to receive a hose nozzle, and camming means on said hose nozzle operable upon said latch when the nozzle is being removed from association therewith to move said latch to the unlatched position whereupon said hub, wall and plate may move to dump hose therefrom.

4. A dumpable hose storage reel, comprising: an upright wall hingedly mounted to swing about a lower horizontal axis, a hub rotatably mounted on said wall to turn about a horizontal axis at right angles to said hinged mount of said wall, a plate forming a flange for said hub opposite said wall and having a lower hinge mount, a latch slidably mounted opposite said hinges and adapted to engage said wall and plate upper edges to normally retain them upright, said slidable latch being adapted to receive a latch pin, and camming means on said latch pin operable upon said latch when the latch pin is being removed from association therewith to move said latch to the unlatched position whereupon said hub, wall and plate may move to dump hose therefrom.

5. A dumpable hose storage reel, comprising: an upright arm hingedly mounted to swing about a lower horizontal axis, a hub rotatably mounted on said arm to turn about a horizontal axis at right angles to said hinged mount of said arm, a plate forming a flange for said hub opposite said arm and having a lower hinge mount, a latch slidably mounted opposite said hinges and adapted to engage said plate upper edge to normally retain it upright, said slidable latch being adapted to receive a hose nozzle, and camming means on said hose nozzle operable upon said latch when the nozzle is being removed from association therewith to move said latch to the unlatched position whereupon said hub and plate may move to dump hose therefrom.

6. A dumpable hose storage reel, comprising: an upright arm hingedly mounted to swing about a lower horizontal axis, a hub rotatably mounted on said arm to turn about a horizontal axis at right angles to said hinged mount of said arm, a plate forming a flange for said hub opposite said arm and having a lower hinge mount, a latch slidably mounted opposite said hinges and adapted to engage said plate upper edge to normally retain it upright, said slidable latch being adapted to receive a latch pin, and camming means on said latch pin operable upon said latch when the latch pin is being removed from association therewith to move said latch to the unlatched position whereupon said hub and plate may move to dump hose therefrom.

7. A dumpable hose storage reel, comprising: a hub rotatably mounted to turn about a horizontal axis, a plate forming an outer flange for said hub and having a lower hinge mount transverse the axis of said hub, a latch slidably mounted opposite said hinge and adapted to engage said plate upper edge to normally retain it upright, said slidable latch being adapted to receive a latch pin, and camming means on said latch pin operable upon said latch when the latch pin is being removed from association therewith to move said latch to the unlatched position whereupon said plate may move and the hose may fall away from said hub.
